Jumbo LED Light Up Holiday Necklace, earliest review Dec. 28, 2016, online. Site visited Jun. 6, 2018. Internet URL:<"<https://www.amazon.com/Jumbo-LED-Light-Holiday-Necklace/dp/B01N3TKJS4>"> (Year: 2016).*

Primary Examiner — Cynthia Ramirez*Assistant Examiner* — L. Martinez*(74) Attorney, Agent, or Firm* — NK Patent Law(57) **CLAIM**

The ornamental design for a necklace, as shown and described.

DESCRIPTION

FIG. 1 is a perspective view of a necklace showing my new design;

FIG. 2 is a front view thereof;

FIG. 3 is a rear view thereof;

FIG. 4 is a left side view thereof;

FIG. 5 is a top view thereof;

FIG. 6 is a bottom view thereof; and,

FIG. 7 is an enlarged front view thereof.

The broken lines in the drawings illustrate portions of the necklace that form no part of the claimed design.

1 Claim, 6 Drawing Sheets(56)
